UNITED STATES PATENT OFFICE

FRANK L. O. WADSWORTH, OF PITTSBURGH, PENNSYLVANIA

MULTIPLE-PISTON PNEUMATIC TOOL

Application filed July 26, 1921. Serial No. 487,589.

This invention relates to fluid actuated impact mechanisms, such as pneumatic riveting and chipping hammers, compressed air drills and the like, which comprise freely movable piston members that are reciprocated at a high speed to deliver a rapidly recurring succession of blows against the heads of relatively stationary tool elements (such as a rivet set or a chisel, or a percussion drill); and one of the primary objects of my present improvements is to greatly increase the driving, or cutting or penetrating power of such devices, without adding to their weight or bulk.

Under the usual conditions of operation—where the action of these tools is dependent only on an impact effect—the maximum capacity of this type of mechanism is determined, in part by the force of each blow and in part by the number of blows delivered per minute. The first factor is measured by the "driving" energy of the piston at the instant of its impact with the operating tool element; and this, in turn, depends on the mass or weight of the reciprocating member and on its maximum velocity, or speed of travel, at that instant of impact. Under a given actuating pressure on the reciprocating members, which is generally fixed by practical conditions, the velocity imparted thereto is directly proportional to the square root of the length of travel, or the "stroke", of the piston, and is inversely proportional to the square root of its mass. It follows from this that the momentum of each impact blow is directly proportional to the square root of the piston stroke and also to the square root of the piston weight, and that the driving or cutting power of each impulse may therefore be increased by using either a larger piston or a longer piston cylinder, or both. But the increase in either of these factors increases the bulk and weight of the mechanism in a much more rapid ratio than the individual power impulse is augmented; and the increase in the effective length of "stroke" decreases the possible number of strokes per minute. The aggregate driving power or working capacity of these tools, as ordinarily constructed, cannot therefore be in-

creased without a great disproportionate enlargement of the size, and weight of the more important parts of the organization; and this in turn adds not only to the first cost of construction and the subsequent expense of operation and maintenance, but also increases the difficulty and the labor of manipulating these larger and heavier mechanisms.

In my improved construction I avoid all of the difficulties above mentioned, and obtain certain new and important results by utilizing a plurality of piston elements to impart a properly controlled series of blows to a single operating tool. All of the reciprocating members are preferably made of substantially the same size and weight and are capable of making substantially the same length of stroke, which is varied according to an arbitrary rating of capacity (e. g. a ten inch stroke for a No. 10 hammer, a twelve inch stroke for a No. 12 hammer, etc.), and the reciprocal movements of the piston elements are controlled and timed, preferably by a single distribution valve, in such manner that when one of the said elements is making its forward or impact stroke, another one is making its rearward or return stroke. The number of blows per minute may thus be increased to any desired ratio, by increasing the number of co-operatively controlled pistons, without any decrease either in the mass or the stroke of each reciprocating element, and without any diminution, therefore, in the driving force of each impulse. A multiple piston tool of my improved construction will, for this reason, possess a driving power which may be two or three times as great as that possessed by the single piston tool of the ordinary construction and of the same rated stroke; and for reasons which will hereafter appear this relatively great increase in the operating capacity of the new type of mechanism may be accompanied by an actual decrease in the bulk and weight of any given size or number (e. g. No. 10) of hammer.

Another object of this invention is to improve the operating balance of reciprocating-piston-impact tools, by the counteracting momentum effects of oppositely moving piston elements, and thus diminish the transmis-

sion of shock and vibration to the hands of the operators.

A further object of my improvements is to produce a fluid actuated impact tool which does not require the introduction of any change of "live air", or live motive fluid, at the front end of the piston chamber, to effect the rearward or return movement of the reciprocating member, and which does not therefore require, or necessitate, the use of long supply and exhaust passages extending from the distribution valve to the tool receiving end of the piston cylinder.

Other objects of my present improvements are to produce pneumatic hammer constructions, which are relatively simple in design and can be readily manufactured without the use of special tools; which are easily disassembled and repaired; and which can be operated at low cost.

As illustrative of my invention I have shown, in the accompanying drawings, three (3) forms or exemplifications of the multiple piston type of impact tools; and in the following description of these exemplifications I have, as far as possible, used the same, or similar reference numerals to denote or designate the same or corresponding parts and elements of the several exemplary organizations.

On the first sheet of drawings, Figure 1 is a longitudinal section through the center of a twin piston pneumatic hammer that embodies my improvements; Fig. 2 is an enlarged cross section on the plane 2-2 of Fig. 1 (or Figs. 3 and 5); Fig. 3 is a fragmentary sectional elevation on the plane 3-3 of Fig. 2; Fig. 4 is a partial section on this same plane, but showing the distribution valve element in another position; Fig. 5 is another fragmentary section on the plane 5-5 of Fig. 2 (at right angles to the plane of the sections shown in Figs. 1, 3 and 4); and Fig. 6 is a cross section on the plane 6-6 of Fig. 1.

The second sheet of drawings illustrate a second embodiment of my improvements. Fig. 7 is a side elevation, partially in section, of this form of construction; Fig. 8 is an enlarged longitudinal section of a part of the hammer shown in Fig. 7; Fig. 9 is another similar view of this same part with the distribution valve element at the opposite end of its movement; and Figs. 10 and 11 are cross-sectional views that are respectively taken on the planes 10-10 and 11-11 of Fig. 7.

Figs. 12 to 17, inclusive, depict a third exemplification of my invention. In these views Fig. 12 is a central longitudinal section through the rear or handle end of a pneumatic riveting hammer; Fig. 13 is a sectional elevation, on the same plane as Fig. 12, of the front or rivet set end of this tool; Fig. 14 is a transverse cross section on the plane 14-14 of Figs. 12-13; Fig. 15 is a longitudinal section on an enlarged scale on the planes 15-15 of Figs. 12-14; Fig. 16 is a transverse section

on the plane 16-16 of Figs. 12 and 15; and Fig. 17 is another view on a still larger scale on this same plane, and shows the distribution valve elements in another position.

In the construction shown in Figs. 1 to 6 inclusive the hammer barrel 4 is provided with two parallel cylindrical chambers, 7 and 8, which extend from the rivet set collar, or sleeve 9, at the front end of the said barrel, to an enlarged cylindrical cavity that receives the valve box 12 at the rear end thereof. The valve box 12 is provided with two openings, which are of the same diameter as the chambers, 7 and 8, and which register therewith, and form extensions thereof when the valve box is in place. Each of these chambers contains a suitable piston element 17, which is adapted to reciprocate freely therein; and which is preferably provided with a slightly convexed striking face that is adapted to engage with the surface of a curved rib 18 on the inner end of the rivet set shank 19, at such an angle that the force of the blows delivered by the piston elements is directed toward the center of the rivet head or other object on which the tool is operating.

The valve box 12 is also provided with two recesses 20 and 21, which are disposed on opposite sides of the piston cylinder extensions therein; and which are adapted to receive respectively the distribution valve element 22 and the control valve 23 that regulate the admission of air to the opposite ends of the piston chambers. Live air is admitted to the rear ends of these recesses through the lateral passages, 24 and 25, which open into the annular chamber 26 that surrounds the rear end of the valve box and communicates at one side with the usual supply duct 27 in the hammer handle. The live air thus admitted to the recess 20 enters the open end of the hollow distribution valve 22 and passes therefrom, through the ring of ports 28, to one or the other of two annular grooves 29 and 30; which are in communication, through the passages 31 and 32, respectively, with two drilled and plugged cavities 33 and 34 (see Fig. 3). The cavity 33 is provided with a transverse opening 35, similar in form to that indicated at 41 in Fig. 2, which enters the side of an eccentric groove 36 in the valve box section of the piston chamber 7; and the cavity 34 is provided with a similar opening 37 that communicates in like manner with the eccentric groove 38 in the valve box section of the other piston chamber 8. The valve box sections of these chambers are further provided with two other eccentric grooves 39 and 40, which are similar in form to the grooves 36 and 38 and which are positioned at a fixed distance in advance of the latter; and these forward channels are in communication with the transverse openings 41 and 42, that enter the drilled and plugged cavities 43 and 44. The cavity 43 is in communication, through an

elongated port 45, with an eccentric groove 46 surrounding the distribution valve 22, and the cavity 44 is in communication, through a similar port 47, with a reversely offset eccentric groove 48. The recess containing the distribution valve is also provided with a third eccentric groove 49 which communicates through the port 50, with the exhaust passage 51 that leads to the outside of the hammer barrel (as best shown in Fig. 5).

The hollow distribution valve 22 has an enlarged central portion, which terminates in the two shoulders 52 and 53 (see Fig. 4), and which carries a flange 54 that slides in a chamber 55; and this central enlargement is provided with a peripheral channel 56 whose width is just sufficient to cover the two adjacent grooves 48-49 (when the valve is in the position of Fig. 3 or the two adjacent grooves 46-49 when the valve is in the position of Fig. 4). The shell of the valve 22 is perforated by the restricted ducts 57 and 58 which serve to admit air, from the recess 20, to the annular chambers which are respectively located in the rear of the shoulder 52 and in front of the shoulder 53. The extreme rear end of the first of these annular chambers is provided with a passageway 59 which leads forwardly to a port 60 in the valve box section of the cylinder 7; and the opposite end of the other chamber, in front of the shoulder 53, is provided with a passageway 61 that leads to a correspondingly positioned port 62 in the piston cylinder 8. The front end of the chamber 55, in which the flange 54 reciprocates, is connected to another port 63, in the front portion of the cylinder 7, by means of the passageway 64; and the rear end of this same chamber is connected to a correspondingly positioned port 65 in the cylinder 8, by means of the passageway 66.

The control valve which is positioned in the recess 21 comprises a plunger, having a stem 23 and a head 67, that is mounted to reciprocate freely in a two-part bushing 68-69. The annular chamber behind the head 67 is connected to the live air channel 25, by means of the groove 70 and the duct 71; and the opening in the rear of the stem 23 is connected to the exhaust channel 51, by means of the ducts 72 and 73 and the peripheral groove 74. The space in front of the head 67 is in communication with the front part of the recess 21 through the port 75; and a passageway 76 leads from the said recess to an opening 77 in the partition wall between the two cylinders 7 and 8 (see Fig. 1). The valve plunger 23-67 is so proportioned that the area of the head portion 67 is about four times the area of the annular shoulder between the said head and the stem 23; and the latter is perforated by a restricted duct 78, that serves to connect the differential area chambers on

the two sides of the said head, when the valve plunger is in the position shown in Fig. 5.

The various bearing surfaces of the reciprocating valve elements (22 and 23-67) are ground to form close but easy sliding fits with their respective casings; and the longitudinal movements of these elements are limited by the bushing caps or sleeves 80 and 68 that engage and cover the front ends thereof. The assembled valve box parts are clamped in position in the cylindrical recess at the rear end of the hammer barrel 4 by screwing on the handle 1, and locking it in place by means of suitable ratchet and dog connections 81-82 (such for example as have been fully illustrated and described in my co-pending application Serial No. 783,794, filed July 11, 1921); and in order to prevent leakage of live air from the annular space 26 to the exhaust passages 50-51 a compressible wedge-shaped packing ring 83, of aluminum or lead alloy or similar material, is inserted between the end of the hammer barrel 4 and an internally turned flange on the recessed hub of the handle member 1. The locking connections 81-82 and the exhaust openings 51 are covered by a spring ring or clip 84 that it provided on one side with discharge openings 85 that direct the exhaust away from the handle portion of the hammer.

The operation of this double piston hammer is as follows: When compressed air, or other motive fluid, is admitted to the passage 27 and the annular chamber 26 (by means of the usual thumb valve on the handle grip), it will force the control valve 23-67 to its forward position, as shown in Fig. 5, and permit the motive fluid to flow through the passages and ports 78-75-76 and 77 until the pressure in the front end of the piston chambers, and the space between the two pistons therein, is a little less than 30% of that in the annular supply reservoir 26. The pressure on the front face of the valve head 67 then overbalances the pressure on the annular shoulder between this head and the stem 23 and the valve is moved rearwardly, thus closing the entry end of the duct 78 and cutting off the further flow of motive fluid to the front of the piston chambers, but leaving that space charged with air at the reduced pressure just indicated. The opening of the supply passage 27 also admits motive fluid, at the full reservoir pressure, to the interior of the hollow distribution valve 22; and thence to the rear end of one of the piston chambers 7 or 8. If the distribution valve is in the position of Fig. 3, the high pressure air flows through the communicating ports and passages 28-29-31-33-35-36 into the rear end of the piston chamber 7 and forces the piston therein forwardly. In this position of the valve the rear end of the other piston chamber 8 is open to the external air through the communicating ports and channels 40-

42—44—47—48—49—50—51 and 85; and the piston in this chamber is therefore driven rearwardly by the low pressure fluid which has been admitted through the control valve 5 23—67 and trapped in the space between the oppositely moving piston elements.

During the first part of this movement the ports 63 and 65 and passages 64 and 66 are open to the low pressure air and the forces 10 acting on the two sides of the valve flange 54 are balanced (see Figs. 1 and 3). In this part of the movement the port 60 is open to the high pressure air in the rear part of the chamber 7 and the port 62 is open to the exhaust. The pressure on the rear of the valve 15 shoulder 52 is therefore greater than the pressure on the front face of the shoulder 53, and the valve is maintained in the position shown in Fig. 3. But when the advancing 20 piston in the cylinder 7 reaches and passes the port 63 the front face of the valve flange 54 is exposed to the high pressure air in the rear of the said piston, while the opposite face is still subjected to the lower pressure 25 of the air that is trapped between the reciprocating members. The valve may be so designed that this superior pressure on the front of the flange 54 will suffice to move the valve rearwardly; but in order to maintain a more 30 perfect and controlled "timing" between the two piston movements I prefer to make the area of the flange 54 considerably less than the area of the shoulders 52 and 53; and thus delay the throw of the valve until the rearwardly moving piston has reached and covered 35 the port 62. When this occurs the escape of air from the space in front of the shoulder 53 is arrested and the live air flowing into this space through the vents 58 immediately 40 raises the pressure therein sufficiently to move the valve rearwardly to the position shown in Fig. 4. This movement places the valve openings 28 in communication with the channel 30 and admits live motive fluid, through 45 the ports and passageways 32—34—37—38, to the rear end of the cylinder 8; and simultaneously establishes communication between the rear end of the cylinder 7 and the external air through the ports and passages 50 39—41—43—45—46—49—50—51—85. The piston in the cylinder 8 is thus driven forward from the dotted line of position of Fig. 1, while the piston in the cylinder 7 is returned by the pressure of the air that remains 55 trapped between the two reciprocating elements. The valve 22 is maintained in the position shown in Fig. 4 by the pressure of the live air on the front shoulder 53, until the advancing piston has passed the port 65 60 (thus exposing the rear of the flange 54 to the motive fluid pressure back of said advancing piston), and the rearwardly moving piston has—simultaneously or subsequently—covered the port 60 and permitted the live air pressure to build up in the rear of the 65

shoulder 52 and throw the valve forwardly, to initiate another cycle of co-operative piston movements. Each piston is thus caused to move in forced time relationship with its mate and to deliver a regularly recurring series of blows on the rivet set or other operating tool at the forward end of the hammer; and the time ordinarily lost by the return of the piston element to the rear of the hammer barrel (in preparation for the succeeding stroke) is completely eliminated. 70

In the construction shown in Figs. 7 to 11, inclusive, the two piston elements 17a and 17b are co-axially mounted in concentric piston chambers 7a and 8a, which are separated from each other by a tube 86, and which are connected at their front ends by the port openings 77a and 77b. The tube 86 is engaged at its forward extremity by a block 87, which is set in the end of the rivet set 19, and which is grooved on its sides to form the equalizing ports 77b; and it is held at its rear end in a flanged sleeve 88 that is, in turn, clamped between the end wall of the hammer handle 1 and the adjacent recessed end of the valve box 12a. The outer surface of the sleeve 88 and the inner concentric surface of the valve box, are finished to form the bearing surfaces for the reciprocating distribution valve element 22a; and the enlarged forward portion of this valve constitutes the rear end of the outer annular piston chamber 8a. The engaging portions of the tube 86 and the sleeve 88 are pierced with a row of ports 31a, which are in radial alignment with the ports 28a that pass through the rear end of the valve box and open directly into the annular reservoir 26 in the hammer handle. The inner tube 86 is further perforated with a second row of openings 39a that open into an annular channel 46a between the members 86 and 88; and this channel in turn communicates with another row of openings 45a in the outer sleeve 88. The adjacent inner face of the valve box 12a is provided with a groove or channel 49a which is opposite the openings 45a, and which communicates, through the passages 50a and the annular space 51a, with the radial exhaust ports 51b. The rear portion of the distribution valve, 100 which reciprocates in the annular space between the sleeve 88 and the concentric bearing surface of the valve casing, is provided with an end flange 52a (that traverses the ports 28a—31a) and with an intermediate channeled rib 56a which is pierced with the ports 90—90 and which traverses the opposing openings 45a and 49a. 110

The front part of the valve box 12a—which receives and guides the enlarged forward portion of the hollow valve 22a—is provided with two grooves or channels 38a and 40a which communicate respectively with the annular live air reservoir 26 (through the longitudinal passageways 32a) and with the ex- 120 125 130

haust openings 51a, through the radial ducts 47a. The corresponding portion of the valve shell is perforated with two rows of main ports 91 and 92, which are adapted to register respectively with the channel 38a (when the valve is in the position shown in Fig. 8) and with the groove 40a (when the valve is in the position shown in Fig. 9); and with a third row of auxiliary ports 93, that register with the first-named channel when the valve is in its last-mentioned position (Fig. 9). The valve box is further provided with one or more restricted ducts 57a that lead from the live air reservoir 26 to the annular space in the rear of the valve flange 52a; and also with similar ducts 78a that lead from the passages 32a to the space behind the front shoulder 53a of the distribution element. A longitudinal passage 76a leads from the forward end of the annular piston chamber 8a to a point just back of the live air groove 38a; and this passage is provided with two radial ducts or ports, 94 and 95, one of which registers with the ports 92 (when the valve is in the position of Fig. 8), and the other of which opens into the space behind the shoulder 53a and communicates with the ducts 78a, when the valve has been thrown forward (to the position shown in Fig. 9). The inner piston chamber 7a is also provided with a row of ports 96—96 which open into the extreme rear end of the annular space behind the rear valve flange 52a.

The operation of the last described mechanism is as follows: When the thumb latch of the handle is depressed and live motive fluid is admitted to the annular reservoir 26, one or the other of the piston elements will be driven forward—by the flow of the high pressure air, either through the ports 31a or through the ports 91—and a restricted amount of "wire drawn" fluid will be simultaneously admitted to the front of the piston chambers, and between the two piston elements, through one or the other of the ports 94 or 95 and the passageway 76a. If the distribution valve is in the position shown in Fig. 8, the motive fluid will enter the rear end of the cylinder 8a (through the passages and ports 32a—38a—91) and drive the annular piston 17b forwardly. In this position the rear end of the central cylinder 7a is open to the external air through the ports and passages 39a—46a—45a—90—50a—51a—51b—85; and the piston 17a will therefore be forced rearwardly by the low pressure air that is between it and the advancing piston 17a. During the major part of this movement the rear face of the valve flange 52a is not subjected to any substantial pressure—because the air can escape to the open exhaust, through the ports 96, more rapidly than it can flow in through the restricted ducts 57a—and the pressure on the front face of the shoulder 53a is considerably greater than the differential pressure on the rear face

thereof, because of the difference in the areas of these two faces. The valve 22a is therefore held in its retracted position until the rearwardly moving piston 17a has covered the ring of ports 39a and thus cut off any further escape of air from the rear end of the cylinder 7a. The pressure back of the valve flange 52a is then raised sufficiently to overcome the previously unbalanced pressure on the front shoulder 53a and the valve is moved forward to the position shown in Fig. 9. This movement closes the ports 91 and opens the ports 31a—thus admitting live motive fluid to the rear of the piston 17a and driving the latter forward—and it also closes the ports 45a and opens the ports 92, thereby permitting the air back of the piston 17b to escape to the atmosphere, through the passageways 40a—47a—51b—85, and allowing this member to be returned by the air that is trapped between the two pistons, and is now maintained at the desired pressure by the slow flow of high pressure fluid through the restricted ducts 78a—95. During the major period of this reversed action of the piston-valve mechanism the front face of the valve shoulder 53a is relieved of pressure—by the escape of air through the open exhaust ports 92—and the distribution element is held in its advanced position by the full live air pressure on its rear flange 52a. But when the piston 17b has, in its return movement, reached and covered the exhaust ports 92 (as shown in Fig. 9) the fluid in the rear of this member is trapped in the space between it and the valve flange 53a; and the pressure thereon is increased—by the joint effect of the live air flowing through the restricted ducts 93 and the compression of the trapped fluid by the rearwardly moving piston—until it is sufficient to overcome the opposing forward pressures on the valve flanges; and the distribution element is then thrown to the position shown in Fig. 8. This initiates a new cycle of the previously described movements.

In the operation of this second exemplification of my improved multiple piston organization, the maintenance of the desired pressure between the reversely moving pistons is effected by the relatively slow but continuous flow of motive fluid into the passageway 76a—either through the duct 94, or the ducts 78a and 95—and this flow is so regulated (by a proper proportioning of the areas of the supply passages) as to just compensate for any leakages, from the front of the piston chambers, through the rivet set mounting, or past the rearwardly moving piston to the exhaust. This means of controlling the return pressure on the reciprocating piston elements is not as sensitive and universal in its action as the automatic reduction pressure valve 23—67 which is described in connection with the construction shown in Figs. 1 to 6; but it is sufficiently accurate in its regulation to se-

cure the desired operation of the hammer under very considerable variations in the motive fluid pressure.

The third illustrative embodiment of my invention, which is depicted in Figs. 12 to 17, inclusive, presents several features of structure which are common to both of the previously described mechanisms—and which need not therefore be redescribed in detail—but it presents other features of construction which require additional explanation. For example: The two organizations shown in Figs. 1 to 11, inclusive, are each provided with two pistons; whereas the organization now under consideration has four pistons which operate in pairs in the symmetrically disposed cylinder chambers 7b—7c, and 8b—8c. The cylinders 7b—7c, and the pistons (17c) which work therein, are of somewhat smaller cross-sectional area than the cylinders 8b—8c and the corresponding piston elements (17d); and in order to make the two pairs of reciprocating members of substantially equal weight the length of the pistons 17c is somewhat greater than that of the pistons 17d. The greater length of the first-mentioned members requires a greater length of piston chamber for the maintenance of an equal length of stroke; and this is secured by extending the cylinders 7b—7c through the valve box 12b, (as best shown in Fig. 12) and terminating the cylinders 8b—8c at the forward end of that box (as shown in Fig. 15).

The distribution valve of this four cylinder construction is made in two parts 22b—22c, and is mounted transversely of the valve box between the extensions of the piston chambers 7b—7c. These valve parts are mounted in ground and hardened bushings 98 and 99 which are inserted from opposite sides of the valve box 12b, and are held in place, when the valve box is inserted in the end of the hammer barrel, by the extension sleeve 100 at the rear end thereof. The rear sides 45 of these bushings 98 and 99 are provided with segmental slots 101 and 102 which open into a transverse groove 103 on the back of the valve box 12b, and the ends of this transverse slot communicate with the live air chamber 50 at the base of the hammer handle (see Fig. 12). The valve box 12b is further provided with two sets of longitudinal passageways which are arranged symmetrically on opposite sides of the valve bushings 98 and 99; and which communicate through lateral passageways with two lines of ports in the side walls of the said bushings. The four longitudinal passageways 33b are provided with lateral ports 35b which open into the rear end of the piston cylinders 7b and 7c; and these passageways communicate, through rows of openings 31b with two annular spaces between the inner surface of the valve bushings 98 and 99 and the intermediate channeled portions 104 and 105 of the distribution

valve sections 22b and 22c. The four longitudinal passageways 34b are provided, at their inner ends with transverse ports 37b that open into the rear ends of the cylinders 8b and 8c (best shown in Fig. 15) and at their rear ends with transverse passages 32b, that also communicate with the annular spaces last referred to. The four longitudinal passages 44b are provided, at their inner ends with transverse ports 42b that also open into the rear end of the cylinders 8b and 8c (see Fig. 15), and these passages communicate at their rear ends with the sides of two peripheral grooves 48b on the exteriors of the bushing elements 98 and 99. The adjacent portions of these bushings are perforated with rows of radial ports 47b which serve, in certain positions of the valve elements, to connect the groove 48b with the interior of the hollow distribution valve. The ends of the bushings 98 and 99 are cut away on one side to form forwardly extending slots or channels 106 that register with the rear ends of a series of exhaust passages 51c in the rear end of the hammer barrel 4. The dividing web between the four symmetrically disposed piston chambers is further provided with a transverse passage 41b that connects the rear ends of the cylinders 7b and 7c; and this transverse passage is connected with an oval channel 43b that opens, at its rear end, into the central portion of the distribution valve recess.

The valve box 12b is also provided with two sets of restricted ducts 57b and 58b, which lead respectively from the live air channel 103 to the annular chambers at the outer and inner sides of the valve flanges 52b and 53b; and the adjacent portions of the valve shells, are perforated with rows of small ducts 107 and 108, that are adapted to put the said annular chambers in communication with the interior of the valve when the adjacent flanges are moved away from the contiguous ends of the valve recesses. The portions of the valve casing in which the reduced ends of the valve sections reciprocate are further provided with restricted ports 59b and 61b; and these ports communicate respectively with the ports 60b and 62b in the rear ends of the piston cylinders 7b—7c and 8b—8c.

The forward ends of the four piston cylinders are all connected with each other by an annular opening 109 at the rear of the rivet set sleeve 9; and this annular opening is in communication—through the longitudinal passageway 76b—with a pocket 21 that contains an automatic control valve 23 which is similar to that illustrated in detail in Fig. 5.

In explaining the operation of this third embodiment of my invention it will be assumed that the live motive fluid is admitted to the handle when the valve parts are in

the position shown in the enlarged view of Fig. 17. The high pressure air will then pass, through the slots 101 and 102 and the passages 31b—33b—35b, into the rear ends 5 of the cylinders 7b—7c and drive the two pistons therein forwardly. In this position the rear ends of the cylinders 8b—8c are open to the external air through the communicating ports and passageways 42b—10 44b—48b—47b—106—51c and 85; and the pistons 17d are therefore free to move rearwardly under the effect of the low pressure air which is admitted to the front end of the piston cylinders through the passageway 15 76b by the previously described action of the automatic control valve 23—67. During this phase of the operation the pressures on the opposite shoulders 52b and 53b of the distribution valve elements are substantially 20 balanced; because the live air which is admitted to the annular chambers back of the shoulders 53b (through the ducts 58b) is allowed to pass to the exhausted ends of the cylinders 8b and 8c through the now opened ports 61b and 62b; and the live air that enters the chambers in front of the valve shoulders 52b (through the ducts 57b) is allowed to pass to the exhaust directly through the vents 107. But the valve sections are 25 maintained in position, in part by the frictional resistance to their movement, and in part by the kinetic pressure effect of the streams of live motive fluid that are flowing from the slots 101 and 102 inwardly toward the port 30 openings 31b. But when the rearwardly moving pistons 17d cover the exhaust ports 42b the escape of air from behind the valve flanges 53b is retarded; and when the continued rearward movement of the pistons 40 has covered the port 62b such escape is completely arrested; and the rapid resultant building up of the pressure in the now closed chambers back of the flanges 53b throws the valve sections 22b and 22c outwardly from 45 the position shown in Fig. 17 to that shown in Figs. 15 and 16.

In this second position of the parts the ports 31b are closed and the ports 32b are opened, thus allowing the live motive fluid 50 to flow into the rear ends of the piston chambers 8b—8c and drive the pistons therein forwardly. The outward movement of the valve sections also opens the elongated exhaust port 43b, and allows the air in the rear 55 ends of the piston chambers 7b—7c to flow through the interior of the hollow valve sections and pass to the outside of the hammer through the passageways 106—51c and 85. In this phase of the operation the pressures 60 on the end flanges of the distribution valve sections are balanced by the escape of air from the annular chamber back of the flange 53b through the now opened vents 108 and by the escape of air from the annular chamber 65 outside of the flange 52b through the

ports 59b and 60b; but the valve parts are maintained in position, as before, by the frictional resistance to their movement and by the kinetic pressure effects of the live air flow through the slots 101 and 102 to the 70 port openings 32b. When the rearwardly moving pistons 17c reach and close the exhaust openings 41b the further escape of air from the chambers in front of the shoulders 52b is retarded; and when these pistons, 75 in their continued rearward movement reach and cover the ports 60b that escape is completely stopped. The instantly augmented live air pressure on the outer shoulders of the valve elements then throws these elements to the first described position (illustrated in Fig. 17) and the various parts are 80 in position to repeat the above-described cycle of movements.

In order to obtain the most efficiently synchronized action of the reversely moving pistons it is, in some cases, desirable to so proportion these elements that they will have the same natural period of reciprocation rather than the same mass. If we ignore the retarding effect of friction (which is usually very small) and the effect of gravity (which may act in some cases to retard and in other cases to accelerate the movement) and assume that the effective pressure of the motive fluid on 90 the face of the piston remains substantially constant during the full stroke thereof; the time, t , of each recurrent movement is 95

$$t = \sqrt{\frac{2ms}{Ap}}$$

where m is the mass of the piston, s is the distance through which it has moved from rest—i. e., the stroke of the hammer— A is the area exposed to the motive fluid and p is the effective pressure. In the case of cylindrical pistons, the mass is equal to the area, A , multiplied by the length, l , and the density, D , of the reciprocating element, and the above expression may therefore be written 105

$$t = \sqrt{\frac{2Dls}{p}}$$

In the particular form of construction illustrated in Figs. 1 to 6, the two piston elements are identical in form and character, and have equal lengths of stroke (s). In this case, both the masses and the natural periods of reciprocation of the two elements are the same. But 115 in the constructions shown in Figs. 7 to 11 and 12 to 17, inclusive, one set of piston elements (17a or 17c) is longer than the other set (17b or 17d) and each reciprocating member has substantially the same stroke s . If the 120 hammer is to be so designed that each piston shall have the same natural period of reciprocation (t), the product Dl must remain constant; and the mean density of the longer pistons must therefore be less than that of 125 130

- the shorter pistons. This result can be attained most conveniently by making the longer pistons (17a or 17c) of the form shown in Fig. 1 or Fig. 7. In this form the rear end 5 of the piston is provided with a cavity 110, which may either be covered by a cap 111—that is pressed and welded in place to form a substantially integral part of the piston body—or may be left open as shown in Fig. 7.
- 10 The hollow or recessed form of piston last described may also be employed with advantage in certain types of hammer construction in which either single or multiple pistons are used. In percussion impact tools, the useful effect (e) of each blow is determined in 15 part by the kinetic energy of the moving piston at the time of impact—which is measured by the product of the mass (m) times the square of the velocity (v^2) of the piston element—and in part by the character of the work to be performed—which controls the ratio between the kinetic energy of impact and the useful work accomplished by the impact actuated member. The aggregate effect 20
- 25 (E) of a succession of blows depends upon the individual effect (e) of each blow and upon the total number (N) of such blows; and the driving or cutting power (P) of the tool is, in general, measured by the integrated effect (E) of these two factors in a fixed interval (or unit) of time.
- 30 Under the conditions assumed in the preceding paragraph, the velocity imparted to a piston of length l and density D and having 35 a stroke s is

$$V = \sqrt{\frac{2fs}{m}} = \sqrt{\frac{2ps}{Dl}}$$

40 where f is the force acting, and if we assume that the time of the return stroke is approximately the same as that of the impact stroke, the number of complete reciprocations (or 45 blows) of a single piston in a given interval of time (T) will be

$$N = \frac{T}{2t} = \frac{T}{2} \sqrt{\frac{p}{2Dls}}$$

50 If all of the kinetic energy of each blow could be converted into useful work the effect (e^m) of such blow would be

$$e^m = \frac{1}{2}mv^2; \text{ or } \frac{1}{2}m \cdot \frac{2fs}{m} = fs = Aps$$

55 and the driving power of each piston element for a given interval of time (T) will be

$$E^m = e^m N = Aps \cdot \frac{T}{2} \sqrt{\frac{p}{2Dls}}$$

60 or for unit of time (T=1)

$$P^m = \frac{A}{2} \sqrt{\frac{p^3 s}{2Dl}} = \sqrt{\frac{A^3 p^3 s}{8m}}$$

65 Under such circumstances, the effect of each blow (e^m) would be independent of the mass

of the piston but would be directly proportional to the cross-sectional area of the reciprocating member and to the length of its stroke. But the aggregate effect (E^m) of a 70 succession of impacts, on a uniformly resistant object, would vary inversely as the square root of the mass (m) of the striking member; and in such a case it would, therefore, be an advantage to decrease that mass, without decreasing the cross-sectional area 75 (A), or the bearing length l , by the use of the form of hollow piston element that is shown in Figs. 1 and 7.

Under other conditions of operation, the practical effect (e) of each impact stroke 80 represents considerably less than the maximum kinetic energy (e^m) that is imparted to the striking piston; and in many cases this effect (e) is more nearly proportional to the momentum of piston movement (mv) than it 85 is to the energy thereof

$$\left(\frac{1}{2}mv^2 \right).$$

In such cases

$$e = mv = \sqrt{2fsm} = A \sqrt{2Dlps}$$

and the cumulative action of a series of such blows (each of which produces the same effect) is represented by

$$E = eN = mv \times \frac{T}{2t} = A \sqrt{2Dlps} \times \frac{T}{2} \sqrt{\frac{p}{2Dls}}$$

or for unit time (T=1)

$$P = \frac{A}{2} \cdot p$$

If the character of the work is such that the momentive effect of initial individual 105 blows is of relatively great importance—as in certain hot riveting or forging operations—it will be of advantage to increase the mass (m) of the striking piston; and this can be best accomplished by increasing its density 110 D (in such a manner as is described in my co-pending application Serial No. 483,794 filed July 11, 1921, Patent No. 1,739,338 granted Dec. 10, 1929) without increasing its length (l) and thereby diminishing its possible 115 length of stroke (s). But when the aggregate effect of a recurrent succession of uniformly acting impulses is to be considered (as in the majority of chipping and drilling operations); and the cumulative momentive action 120 (E) or effective power (P) is of primary importance, the density of the piston member, and its length of stroke, are immaterial, and the cross-sectional area (A) is the only factor that requires consideration. Under such circumstances also, it is advantageous to employ the hollow or recessed form of piston element (shown in Figs. 1 and 7) because that form is lighter than a solid form having the same pressure-receiving area (A) and the same 130

bearing length (l). This last advantage is particularly characteristic of the four piston construction shown in Figs. 12 to 17; because in that embodiment of my invention the ratio between the effective pressure area (A) of the moving pistons and the mass thereof is increased both by the utilization of the recessed form of construction for the pistons 17c—17c, and also by the division of each impact element into two cylindrical members, whose aggregate cross-sectional area is considerably greater than that of a single piston of the normal and usual size and weight.

While I have illustrated and described several embodiments of my invention, it will be apparent to those skilled in the art that other modifications, additions and omissions may be made in the apparatus illustrated without departing from the spirit and scope 20 of the invention, as set forth by the appended claims.

I claim as my invention:

1. In a pneumatic tool, a casing, two piston chambers enclosed within said casing 25 and in open communication at their forward ends, a free piston located in each chamber, means for delivering motive fluid to the communicating ends of said chambers between the pistons, and means responsive to variations of pressure within the chambers 30 for controlling the delivery of motive fluid to and the discharge of motive fluid from the rear ends of said chambers.

2. In a pneumatic tool, a casing, two piston chambers enclosed thereby, having their forward ends in open communication, a free piston located within each chamber, means responsive to the fluid pressure trapped in said chambers between said pistons for controlling the delivery of motive fluid to the communicating ends of said chambers, and means for controlling the delivery of fluid to and the discharge of fluid from the rear ends of said chambers.

45 3. In a pneumatic tool, a casing, two concentric cylinders located therein, a separate piston operating in each cylinder, a valve box located in the casing and surrounding the rear ends of said cylinders, and a sleeve 50 valve located in said box and surrounding the rear ends of the cylinders for controlling the delivery of operating fluid to said cylinders.

55 4. In a pneumatic tool, a casing, two concentric cylinders located therein and in communication at their forward ends, a separate piston operating in each cylinder, a valve box located within said casing at the rear of said cylinders and in line therewith, a sleeve valve, located within the box and encircling the rear ends of the cylinders, for controlling the delivery of operating fluid to the rear of said pistons, and for maintaining 60 a decreased fluid pressure at the forward

ends of said cylinders in front of said pistons.

5. In a pneumatic tool, a casing enclosing two piston chambers in open communication at their forward ends, a separate free piston located in each chamber, a member extending into said casing and engaged by both of said pistons at the forward limit of their strokes, means for alternately delivering high pressure motive fluid to said chambers behind said pistons and for alternately exhausting said chambers, and means for maintaining a reduced operating pressure in the communicating ends of said chambers ahead of said pistons.

6. In a pneumatic tool, a casing enclosing a plurality of piston chambers in open communication at their forward ends, a separate free piston in each chamber, a member extending into said casing forming a closure for the forward end of all of said chambers, and adapted to be engaged by said pistons, a distributing valve responsive in operation to variations in fluid pressure within said chambers for delivering high pressure fluid first to one and then another of said chambers and for exhausting one and then another of said chambers and means for maintaining a reduced fluid pressure in the communicating ends of said chambers.

7. In a pneumatic hammer, a casing enclosing two piston chambers in open communication at their forward ends, a free piston operating in each chamber, a rivet set extending into said casing and adapted to be engaged by both of said pistons, means responsive to variations in pressure in both chambers for controlling the delivery of fluid to and the discharge of fluid from the rear ends of said chambers and for maintaining a determined fluid pressure in the communicating ends of said chambers.

8. In a pneumatic tool, a casing enclosing two concentric piston chambers, in open communication at their forward ends, a member extending into the forward end of said casing and adapted to be engaged by both pistons, means for controlling the delivery of motive fluid to and the discharge of motive fluid from the rear ends of said chambers, and means for maintaining a predetermined operating pressure in communicating ends of said chambers.

In testimony whereof, I have hereunto subscribed my name this 25th day of July, 1921.

FRANK L. O. WADSWORTH.
